UNITED STATES PATENT OFFICE.

BENJAMIN A. HAM, OF BOSTON, MASSACHUSETTS.

CEMENT BUILDING CONSTRUCTION.

1,117,040.

Specification of Letters Patent. Patented Nov. 10, 1914.

Application filed August 3, 1914. Serial No. 854,685.

To all whom it may concern:

Be it known that I, BENJAMIN A. HAM, a citizen of the United States, residing at Boston, in the county of Suffolk and State 5 of Massachusetts, have invented an Improvement in Cement Building Construction, of which the following is a specification.

This invention relates to certain improvements in construction of buildings having a wooden frame-work, or studding, which is covered on the exterior with a veneer of relatively thin cement blocks, and, more particularly relates to certain improvements 15 in cement blocks adapted for such purpose, and the means associated therewith for attaching them to the studding, and the manner in which they are attached. Prior to my invention, cement blocks have been provided with attaching means which comprise 20 a reinforcing rod, having wires attached thereto, said rod and attached portion of the wires being embedded in the block and said wires extended beyond the inner surface of 25 the block and being adapted to be connected to the frame of the building to hold the blocks in place. In the practical employment of these attaching means various difficulties are presented. It is difficult to cast 30 the blocks so that the wires which are attached to the rod will project from their inner sides, inasmuch as the most convenient method of making the same is to cast them in a shallow mold, and, as the upper 35 surface of the block must be the finished surface, the side next the bottom must be the inner side of the block, from which the wires must project, furthermore, said projecting wires are liable to be broken in setting 40 the block in place, in which case the entire block might be rendered useless.

The object of my invention is to provide the blocks with means, which are adapted to be entirely embedded in the cement at 45 the time the block is cast, so that they do not protrude beyond the surface of the block, thereby enabling the block to be cast in a shallow mold and its upper surface to be finished as desired before the cement 50 hardens, and avoiding the necessity of having attaching means protrude through the bottom of the mold, when the block is cast, said means being adapted to receive attaching means, at any time after the block has 55 been removed from the mold, or when it is placed in position against the studding,

which may be employed to bind the block securely to the studding and to draw the blocks closely together at their ends. I accomplish this object by the means shown in 60 the accompanying drawing, in which:

Figure 1 is an elevation of the inner side of a cement block provided with my invention. Fig. 2 is a cross sectional view thereof on the line 2—2 Fig. 1. Fig. 3 is an elevation showing the inner side of the building studding with the cement blocks attached thereto in a manner embodying my invention. Fig. 4 is a top plan view thereof. Fig. 5 is a cross sectional view of a mold 65 for forming the blocks, illustrating the method which I preferably employ in making said blocks. Fig. 6 is a detail view of the fastener-receiving means which I employ. 70

According to my invention, in the process of manufacture of the cement blocks *a*, a reinforcing rod *b* is embedded in the middle of each block, said rod being of sufficient length to extend from end to end thereof, 75 and a series of U-shaped tubes *c* are also embedded therein, and arranged to extend around said rod with their ends flush with the inner surface of the block.

In practice, the blocks are cast in shallow 85 molds, as *d*, preferably between two and three inches in depth, and of the required length and breadth, and when the mold is partly filled the rod *b* is laid therein. The ends of the tubes are closed with some readily removable means, as a cork stopper *e*, and then said tubes are inserted in the cement astride the rod and pressed down until their ends touch, or bear against the bottom of the mold, as shown in Figs. 5 and 90 6. The filling of the mold is then completed, so that the rod and tubes are covered, and the top surface is finished as desired. Numerous different effects in finish may be 95 conveniently secured on the upper surface 100 of the block when cast in this manner, as it is convenient of access and special finishing material may be applied to this surface before the cement hardens.

After the cement hardens and is removed 105 from the mold, a cement block will be provided having one or more reflexed passages therein, which open to the inner side of the block, or the side which is to engage the wall of the structure when in position 110 thereon.

In the construction of the building, the

studs *f* are arranged at the customary distance apart, and the blocks *a* are made of such length that they will extend from the middle of one stud to the middle of the 5 second stud therefrom. In constructing a wall of said blocks, the blocks are placed edge to edge against the outer sides of the studs, so that the inner sides of the blocks rest thereagainst, and the ends of the blocks 10 of one course terminate directly opposite the middle of the blocks in the adjacent courses.

Either before, or after the blocks are placed in position against the studs, the 15 corks *e* are removed from the ends of the tubes *c*, and a length of strong, flexible wire *g* is pushed through each tube, this being easily possible, as said tube is of curved form. When said tubes *c* are placed in position at the time the blocks are cast, they 20 are arranged so that, when the blocks are in position against the studs, each tube will be closely adjacent one side of a stud. Further, I preferably arrange one of said tubes 25 adjacent each end of each block, so that the wires which are placed therein protrude adjacent the adjacent sides of the studs which the block partly overlaps, and arrange two tubes adjacent the middle thereof, so that 30 the wires therein are disposed at opposite sides of the stud which engages the middle portion of the block. Each end of one middle wire is then attached to the corresponding end of the other middle wire by merely 35 twisting said ends together, after they have been passed about the inner side of the stud, so that the block is firmly attached to the stud, and, in like manner, the ends of the wire in each of the end tubes are passed 40 about the adjacent stud and connected to the wires in the adjacent tube of the next block. In fastening said end wires the blocks are drawn together so that the cement which is 45 placed between the ends of the blocks will be pressed therebetween, making a close joint. For convenience in illustration, the ends of the wires are shown as twisted together at the inner sides of the studs, but, in practice, they are preferably twisted 50 together at the intermediate sides, so that there will be practically nothing to interfere with the application of the laths to the inner side at any point.

It will be observed that, after a length 55 of wire has been cut off and inserted in a tube, so that both end-portions of the wire extend from the ends of the passage formed thereon, the wire may be readily slid back and forth as desired, so that the relative 60 lengths of said protruding end-portions may be varied, as may be convenient in attaching the same to the studs.

The erection of the wall will be continued 65 in a manner which will be obvious, and, when it is finished, its interior may be pro-

vided with a coating of waterproof material to prevent the passage of moisture therethrough and the usual lath and plaster finish will then be applied.

The U-shaped tubes, while serving primarily as a convenient means of connecting the attaching wires after the blocks are cast, also serve to protect the wires from moisture entering through the block, so that the possibility that the wires may become rusted away in time is avoided, and, to prevent all possibility that this may occur, the tubes are preferably made of waterproof material.

While the above described invention is believed to be especially advantageous when used in connection with a building frame composed of studs, beams, posts, and the like, and is more particularly designed, specifically, for use in this connection, it may be employed in connection with the wall of any structure through which the attaching wires may be passed, so that they may be secured on the inner side thereof.

I claim:—

1. A concrete block constructed to be placed against the outer side of a structure and having a fastener-receiving tube embedded therein and opening at each end to the inner face of the block.

2. A concrete block constructed to be placed against the outer side of a structure and having a U-shaped, fastener-receiving tube embedded therein and opening at each end to the inner face of the block.

3. A concrete block constructed to be placed against the outer side of a structure and having a U-shaped tube embedded therein and opening at each end to the inner side of the block, and a wire extending through said tube and having its end portions adapted for attachment to the structure.

4. A concrete block constructed to be placed against the outer side of a building frame and having a pair of U-shaped tubes embedded therein and opening at opposite sides of a stud-engaging portion of the block, and a flexible wire extending through each tube, the end portions thereof being adapted to be extended about a building frame stud and to be connected together.

5. A concrete block constructed to be placed against the outer side of a structure and having a reinforcing rod and a U-shaped fastener-receiving tube embedded therein, said tube extending about said rod and opening at its ends at the inner side of the block.

6. A concrete block constructed to be placed against the outer side of a structure and having a reinforcing rod extending from end to end, and a U-shaped tube extending about said rod, said rod and tube being embedded in the block and said tube opening at its ends, at the inner side thereof, and a

flexible attaching wire disposed in said tube and having its end portions adapted for attachment to the structure.

7. A concrete block constructed to be placed against a structure wall and having a reflexed fastener-receiving passage therein opening at both ends to the wall-engaging face of the block, at different points therein.

8. A concrete block constructed to be placed against a structure wall and having a reflexed passage therein opening at both ends to the wall-engaging face of the block, and an attaching wire slidably arranged in said passage and extending from both ends thereof to engage the structure wall.

9. A concrete block constructed to be placed against a structure wall and having a reflexed passage therein opening at both ends to the wall-engaging face of the block, and a flexible attaching device slidably arranged in said passage and extending from both ends thereof to engage the structure wall. 20

In testimony whereof, I have signed my name to this specification, in the presence 25 of two subscribing witnesses.

BENJAMIN A. HAM.
